DESIGN FOR A STOCKING DARNING LAST

Martin Bowerman, Glendale, Calif.

Application May 15, 1945, Serial No. 119,550

Term of patent 14 years

(Cl. D3—19)

To all whom it may concern:

Be it known that I, Martin Bowerman, a citizen of the United States, residing in Glendale, Los Angeles County, California, have invented a new, original, and ornamental Design for Stocking Darning Lasts, of which the following is a specification, reference being had to the accompanying drawing forming part thereof.

Fig. 1 is a perspective view of a stocking darning last showing my new design.

Fig. 2 is a vertical sectional view taken through the center, and

Fig. 3 is a plan view thereof.

I claim:

The ornamental design for a stocking darning last, as shown.

MARTIN BOWERMAN.
